UNITED STATES PATENT OFFICE.

MAX OPPENHEIMER AND SAMUEL L. ASHENFARB, OF NEW YORK, N. Y.

ATTACHMENT ON FRAME FOR HAND-MIRRORS.

1,272,703.

Specification of Letters Patent. Patented July 16, 1918.

Application filed April 24, 1918. Serial No. 230,403.

To all whom it may concern:

Be it known that we, MAX OPPENHEIMER and SAMUEL L. ASHENFARB, both citizens of the United States of America, and both 5 residing at New York, in the county of New York and State of New York, have invented certain new and useful Improvements in Attachments on Frames for Hand-Mirrors, of which the following is a specification.

10 Our invention relates to frames for hand mirrors or the like and one of its objects is to provide an attachment in the form of a readily removable adjustable handle which shall serve three purposes, to wit:—(1) a 15 handle by which it may be held in the hand, (2) a base or support for the frame when not so held but is permitted to rest on a fixture and (3) a hook when hung from a catch, each function depending on its then 20 intended use.

Another object of our invention is to provide a construction of such a character that when the attachment above referred to serves 25 as a handle or as a hook, it will become self-locked into its position and a rigid part of the frame, without the use of any additional parts.

A further object of our invention is to render the attachment easily and readily 30 removable without the use of a tool.

A further object is to provide a simple and inexpensive construction.

With all of the foregoing and other objects in view, our invention consists in the 35 construction, combination and arrangement of parts as will be more fully described and set forth hereinafter in the appended claims.

In the accompanying drawing, which forms part of this specification, Figure 1 40 shows a hand mirror equipped with our novel attachment, the attachment being shown in the position it occupies when used as a handle. Fig. 2 is a perspective view of such mirror and attachment in reduced 45 size, showing the attachment swung into the position of a support or base for the mirror when not held by hand. Fig. 3 is a cross section on line 3—3 of Fig. 1. Fig. 4 is an elevation of a hand mirror with a 50 modified construction of the frame, showing an additional appurtenance which we shall hereafter call a yoke or shoulder.

In the present example we have shown 55 the attachment as applied to the frame of a hand mirror. It is, however, understood that our invention is just as applicable to

frames for other articles where such an attachment may be desirable.

Referring specifically to the drawing *a* denotes a mirror, (which is here shown as circular but which may be in any shape or form) mounted in a frame *b* of the usual construction, (which is here shown as ring shaped but which may be likewise of any shape or form). Attached to the outer circumference of the frame *b* is a strip *c* of metal or other suitable material, the ends of which are bent away from the frame to form two lugs *c'*, which slightly deviate from the parallel to the outward from the 60 points of attachment to their end. Near its base each lug is perforated as at *c*². For the purpose to be hereinafter stated, the inner opposite surfaces of the lugs may be fluted or grooved and either throughout their 65 entire length or near their free ends as clearly shown at *c*³ in Fig. 3. A member *d* preferably made of a single wire, rod, bar or tubing of metal of circular cross section, as shown in Fig. 3, is bent upon itself and 70 then is formed with laterally turned or bent ends *d'* which are adapted to be inserted into and to engage the perforations *c*² provided in the lugs *c'* so as to rotate therein 75 and to be readily removable therefrom. 80 This member *d*, when supported in or engaging the lugs and extending longitudinally of the latter, will form a handle for the mirror as shown in Figs. 1 and 4, but when 85 swung on its pivots front or rearwardly will 90 form a base or support for the mirror as shown in Fig. 2. In the latter position of the member *d*, the lugs will serve as the feet 95 of the mirror.

Owing to the resiliency of the member *d*, 95 the parts of its arms near the lateral bends thereof, when the member extends longitudinally of the lugs, will be caused to engage the flutes or grooves of the lugs and by reason of their spring force will become 100 locked therein so that the handle will be rigid with the frame. In this position it is used either as a hand or hanging mirror.

Taking the mirror with its handle in the position just described, if it is then desired 105 to use the mirror by having it stand or rest on a table, mantel or other like fixture, and with that purpose in mind to use the member *d* as a support or base for the frame, the arms of the member *d* are slightly compressed by hand and thereby are released 110 from the fluted surfaces of the lugs so that

the member can be then swung forwardly or rearwardly into the position shown in Fig. 2.

The shape of the member *d*, of course, is optional. It may be curved into the form shown or receive any other ornamental shape. It is essential, however, that the parts thereof near its free ends as at *d*² shall be so bent or curved that when the member 10 *d* is in the position it occupies as a handle, the said parts *d*², by reason of its resiliency and its tendency to rebound to a slightly greater outer extent at the mouth, shall engage the fluted inner surfaces of the lugs and 15 by so doing hold them fixedly in position.

The strip of metal *c* may be fastened in any suitable manner to the frame *b* or the same may be omitted entirely and the frame *b* formed with lugs which are integral parts 20 thereof, and the small open space in the frame resulting in such latter construction may then be inclosed by the insert of a piece of metal connected with the frame.

In Fig. 4 the frame *b* at *e'* is pivotally 25 suspended from or supported by a yoke shaped part *e*. In this case the lugs *c'* are affixed to or formed with said yoke. The member *d* here engages and is supported in the lugs *c'* in the same manner as in the 30 aforesaid modification.

Since the construction of our frame and its attachments aforesaid may be modified in various other ways without deviating from the principle of our invention, we do 35 not wish to restrict ourselves to the details shown and described, but what we claim and desire to secure by Letters Patent is:

1. In a hand mirror or the like, a frame 40 having perforated lugs formed with oppositely directed grooves, a resilient member formed with lateral pivots engaging the perforations of said lugs and capable of engaging the grooves of said lugs to form a handle rigid with said frame and when disengaged from said grooves and turned at an angle to said lugs to form a base or support for said frame, said lugs serving as feet for the mirror when said member is turned at an angle to said lugs.

50 2. A frame for hand mirrors or the like, such frame having a pair of lugs projecting therefrom and formed with oppositely directed grooves and a resilient member given the curvature shown and bent upon itself and each end thereof bent at about a right

angle, said member engaging with its said ends the perforations of said lugs, so that when such member extends longitudinally of the lugs, it will engage said grooves in said lugs and form a handle rigid with said lugs and when swung forward or rearwardly will form a base or support for said frame.

3. A frame for a hand mirror or the like, said frame having a pair of oppositely concaved perforated lugs, a resilient member 65 formed with laterally projecting pivots adapted to removably engage the perforations of said lugs and capable, when extending longitudinally of the lugs, of being engaged by said lugs to form thereby a handle 70 rigid with said lugs and when free of said lugs other than at the point of insertion, of being swung either forward or rearwardly to form a base or support for said frame.

4. In a hand mirror, a frame formed with 75 two perforated lugs projecting from the circumference thereof in a slightly diverging manner and the inner opposite surfaces of which lugs are concaved, a resilient member formed of single piece of metal bent upon 80 itself and the free ends of which, near the terminus, are bent to form pivots adapted to be inserted into and to removably engage the perforations of said lugs, said member, when extending longitudinally of said lugs, 85 being adapted to engage the concaved surfaces of said lugs to form a handle rigid with said lugs and when swung forward or rearwardly to form a base or support for said frame.

90 5. A frame for a hand mirror or the like with a yoke shaped piece pivoted to said frame, said yoke having lugs projecting therefrom and a resilient member pivotally supported in said lugs and adapted when 95 extending longitudinally of said lugs, to form a handle or hook rigid with the latter and when turned forward or rearwardly on its pivots to form a base or support for said frame; the said resilient member being capable of being inserted into and removed from said lugs by a slight pressure of the hand.

100 In testimony whereof we affix our signatures in presence of two witnesses.

MAX OPPENHEIMER.

SAMUEL L. ASHENFARB.
